H. W. MANGOLD ET AL

FLY SWATTER

Filed Sept. 15, 1922

Fig. 2.

UNITED STATES PATENT OFFICE.

HARRY WESLEY MANGOLD AND ANNE MARY MANGOLD, OF SAN JOSE,
CALIFORNIA.

FLY SWATTER.

Application filed September 15, 1922. Serial No. 588,370.

To all whom it may concern:

Be it known that we, HARRY W. MANGOLD and ANNE M. MANGOLD, citizens of the United States, and residents of San Jose, in the State of California, have invented certain new and useful Improvements in Fly Swatters, of which the following is a specification.

This invention relates to fly swatters and 10 more particularly to means for connecting the striking element to the handle.

An important object is to provide a fly swatter having a handle, the forward portion of which is formed with an elongated 15 loop about which a striking element, such as a piece of rubber is extended and the striking element is provided with attaching portions secured to the body of the striking element both inside and exteriorly of the 20 loop whereby a positive and efficient connection is provided between the striking element and the loop.

A further object is to provide a fly swatter 25 which is of highly simplified construction, reliable in use and which is so constructed that the same cannot mar furniture or other objects against which it is struck.

Other objects and advantages of the 30 invention will be apparent during the course of the following description.

In the accompanying drawing forming a 35 part of this application, in which like numerals are employed to designate like parts throughout the same,

Figure 1 is a perspective of the improved 40 fly swatter,

Figure 2 is a plan view of the striking element and a portion of the handle, the view 45 illustrating the means for connecting the handle to the striking element.

Figure 3 is a detail sectional view through 50 the improved fly swatter.

Figure 4 is a fragmentary view illustrating 55 a slight modification of the invention.

In the drawing wherein for the purpose 60 of illustration is shown a preferred embodiment of the invention, the numeral 5 generally designates a handle formed from a single length of wire twisted together as 65 illustrated in Figure 1 and having its intermediate portion arranged in the form of a loop to provide a handle 6 by means of which the fly swatter may be manipulated.

Figure 2 plainly illustrates that the ter-

55 minal portions of the length of wire are arranged in the form of an elongated loop 15 and those portions of the length of wire adjacent the shank of the handle extend diagonally with respect to the longitudinal axis 60 of the handle. In other words the forward portion of the shank is formed with a triangular portion which forms a connecting means for the loop and the shank.

The striking element is designated by the 65 numeral 8 and is formed from a piece of highly flexible and resilient rubber or other material formed with perforations 9 through which air passes so that the free movement of the striking element is not retarded.

In carrying out the invention the rear portion 70 of the striking element is formed with an elongated slot 10 to receive the triangular portion 11 and the striking element 8 is also formed with a longitudinal incision 12 which communicates with the slot 10 and 75 thereby provides a pair of attaching ears or flaps 13.

Figure 1 plainly illustrates that the attaching flaps 13 are extended over the end portion of the loop 15 and as the parallel 80 sides of the loop are arranged in spaced relation to each other the attaching flaps 13 may be cemented within the loop. That is to say those portions of the flaps 13 between the front and rear sides of the loop 15 may be 85 cemented to the body of the striking element and the end portions of the flaps 13 may be cemented to the body of the striking element in advance of the loop. It is thus seen that the flaps 13 are not only secured to the striking element between the front and rear sides of the loop but also in advance of the loop. Another important feature is the fact that the ends of the loop 15 terminate inwardly 90 of the longitudinal edges of the striking element and consequently the flaps 13 may be cemented to the striking element beyond the ends of the loop.

By the particular manner of cementing the flaps 13 to the body of the striking element the wire loop 15 cannot strike the various objects against which the fly swatter is struck and consequently the objects such as furniture would not be marred by the use 95 of the fly swatter.

Attention is also directed to the fact that 100 the ends of the loop 15 are arranged at a point spaced laterally from the longitudi-

nal center of the fly swatter and are confined entirely beneath one of the flaps so that the ends cannot protrude and possibly mar the furniture.

- 5 In the form of the invention illustrated in Figure 4 the body 70 is formed with a flap 71 and the meeting portions of the flap and the body are formed with a transversely extending opening 74 for the reception of 10 the loop 75 of the handle 76. Attention is directed to the fact that the loop 75 may be passed through the opening 74 and positioned flatly in contact with the body 70. This permits the flap 71 to be glued or otherwise secured flatly in contact with the body 70 interiorly and exteriorly of the loop whereby a secure and positive connection of the striking element with the handle is obtained. Also it will be observed that the 20 loop terminates a substantial distance inwardly of the edges of the body and consequently a rather wide bearing surface is provided at all points all of which contribute to the durability of the device.
- 25 With reference to the foregoing description taken in connection with the accompanying drawing, it will be apparent that the improved fly swatter is extremely durable and efficient as the connection between the striking element and the shank is not easily broken as a result of hard use of the device. Further the specific means for connecting the striking element to the shank

30 prevents the woodwork or objects struck by the fly swatter from being marred or scratched.

Having thus described the invention, what is claimed is:—

1. A fly swatter comprising a flexible striking element having its rear portion 40 formed with a transversely extending loop and a longitudinally extending incision communicating with the loop and opening out through the rear end of the striking element whereby to provide a pair of L-shaped attaching straps, and a handle formed from twisted wire having its forward portion formed with a loop and a triangular portion, said straps being extended over the loop and cemented to the striking element between 45 the sides of the loop and in advance of the same.

2. A fly swatter comprising a body having its rear end formed with a flap, the meeting portions of the flap and the body being formed with an opening, and a handle having a loop passed through said opening and arranged flatly in contact with the body, the flap being pasted flatly in engagement with the body interiorly and exteriorly of 50 the loop.

3. The construction set forth in claim 2, said loop terminating inwardly of the edges of the body.

HARRY WESLEY MANGOLD.
ANNE MARY MANGOLD.
